UNITED STATES PATENT OFFICE

HARRY H. KEPLEY, OF PHILADELPHIA, PENNSYLVANIA

TIE HOLDER

Application filed April 5, 1932. Serial No. 603,371.

This invention relates to an improved necktie holder and support, the purpose of the invention being to provide a holder so constructed as to engage the collar button under the tie, with a sharpened point which pierces or enters the tie near the upper part of the knot thereof, in combination with a forwardly and downwardly disposed tongue upon which the knot of the tie rests, thereby supporting the knot and holding the upper part of the knot in very close position to the upper edge of the collar, giving the tie a neat appearance in every way.

Another purpose is to provide a support or holder constructed from a single piece, the sharpened prong being stamped out of the single piece and up-struck from the holder to pierce the knot of the tie while the forwardly and downwardly disposed tongue engages under and supports the knot.

By constructing the sharpened prong from the upwardly and downwardly extending tongue as is shown, it is possible to conserve considerably on the cost of manufacturing the holder.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawing and claimed.

In the drawing:—

Figure 1 is a view in perspective of the improved holder for ties.

Figure 2 is a sectional view on line 2—2 of Figure 1.

Figure 3 is an enlarged detail view of the holder removed.

Figure 4 is a view of a modified construction of holder.

Referring to the drawing 1 identifies the

holder as a whole, and which, in Figures 1, 2, and 3, is stamped from a single piece of metal, forming a body portion 2 provided with an opening 3. This opening consists of a circular part 4, which adjoins a restricted portion 5, the purpose of the circular part being to permit of the passage of the head of a collar button 7, so that by a downward movement of the body of the holder the narrow portion of the opening may engage with the shank of the collar button, thereby preventing detachment of the holder.

In forming the holder the single piece of metal is bent at 8 to form a tongue 9, which is bent slightly at 10. This tongue inclines outwardly and downwardly and is adapted to engage under the knot 11 of the tie, thereby supporting the knot and holding it in very close position adjacent the upper edge of the collar, where the two parts of the collar overlap, preventing the knot from falling down and insuring a neat appearance on the wearer. Struck up from the tongue is a sharpened prong 12, which is located at a point where the tongue is slightly bent. This prong is relatively slim, tapered and sharpened, in order to easily enter the knot of the tie, additionally supporting the knot, as well as preventing the holder from tilting to one side or the other relative to the collar button.

In Figure 4 the holder is slightly modified to the extent that instead of the sharpened prong being struck up from the tongue, the sharpened prong 13 in this instance is in the form of a separate pin soldered or electrically welded to the tongue, otherwise the holder is substantially the same as in Figures 1, 2 and 3.

The invention having been set forth, what is claimed is:

A necktie holder constructed from a single piece of sheet metal, consisting of a body having an opening for passage of the head

of a collar button, whereby a portion of the opening may receive the shank of the collar button, said body having a tongue bent forwardly and downwardly therefrom for engaging under the knot of a necktie whereby the knot may rest thereon for supporting the knot, and a sharpened prong rising from the tongue where it is first bent downwardly and adapted to pierce the knot of the tie, thereby additionally insuring the supporting of the knot in a substantially close position to the upper edge of a collar, as well as preventing the knot from loosening.

In testimony whereof I affix my signature.

15 HARRY H. KEPLEY.
